UNITED STATES PATENT OFFICE.

ABRAHAM H. SHOCK AND WILLIAM L. KENDIG, OF LANCASTER, PENNSYLVANIA, ASSIGNORS TO H. O. B. KENDIG, OF LANCASTER, PENNSYLVANIA.

COMPUTING-SCALE.

No. 825,247.

Specification of Letters Patent.

Patented July 3, 1906.

Application filed January 31, 1903. Serial No. 309,842.

To all whom it may concern:

Be it known that we, ABRAHAM H. SHOCK and WILLIAM L. KENDIG, citizens of the United States, residing at Lancaster, in the county of Lancaster and State of Pennsylvania, have invented certain new and useful Improvements in Computing-Scales; and we do hereby declare the following to be a full, clear, and exact description of the invention, such as will enable others skilled in the art to which it appertains to make and use the same.

This invention relates to computing-scales; and it consists mainly of certain details of construction and combination of the computing-tablet and its indicator, which is also a supplemental poise, and in an improved pivot and bearing for the scale-beam which carries the said tablet.

In the accompanying drawings, Figure 1 represents a front elevation of our scale and chart with the cap of the bearing-block removed. Fig. 2 is a view of a portion of said chart as seen from the opposite side. Fig. 3 is an elevation of a portion of said chart, on a greatly enlarged scale, illustrating the arrangement of the red and black figures hereinafter described. Fig. 4 is a perspective view of our bearing-block. Fig. 5 is a plan view of the bearing-standard and the bearing-block. Fig. 6 is a side elevation of the bearing-block, and Fig. 7 is a vertical section through the chart and indexes.

A designates the frame of a platform-scale; B, the graduated tare-beam; C, the main poise, hung to the outer end of said beam by a link C'; D, the auxiliary poise, sliding on said graduated beam; E, the scoop-poise; F, the rod, partly broken away, connecting the said beam to the weighing-levers under the depressible platform (not shown) and hung from said beam by link F'; G, the graduated computing-panel, which has bifurcated feet g at its ends fitting astride raised parts b of said beam and detachably fastened thereto by screws g', and H a standard rigid with the said frame, having the said beam pivotally mounted thereon. The said standard is bifurcated, as usual in such scales, to receive the middle part of said scale-beam, and each of the upright bearings H' thus formed is provided with the ordinary recess h in its top to receive a bearing-block I, of agate or other hard material, which has a V-shaped groove

in its top. In these grooves of the two bearing-blocks the knife-edged pivots of the scale-beam rest in the ordinary way. 55

It will often happen that such a knife-edge will not be precisely parallel to the axis of the pivot, but will slant downward outwardly or inwardly or be otherwise slightly uneven, especially after long use or repairs. The same may also be true of the bottom line of the V-shaped groove in some instances, though less often, by reason of the greater hardness in 65 the bearing-block. When the knife-edge and the bottom line of the groove do not make a perfect fit, as in the above instances, the pivot, under the weight of its beam and attachments, will bear unequally on the block, 70 tending to break it at one edge or the other. To prevent this, automatic means of compensation by self-adjustment of the block have sometimes been employed by forming conical recesses in the bottom of the block 75 which fit loosely on fixed cones, the latter becoming pivots for the block; but this expedient obviously weakens the block and subjects it to an injurious wedge action at the weakest point, so that there is risk of splitting or fracturing it under the strain of weighing. This objection applies, in greater or less degree, to every compensating construction which involves making a recess or 80 recesses in the block. To secure the benefits 85 of such compensation without thus weakening the block, we leave its bottom unrecessed and set it into shell, cup, or casing L, of thin metal, the four side flanges of which are turned up against the sides of the block, covering the lower part of each of its faces, lugs l being cut out from two of these flanges and turned down horizontally in the plane of the flat bottom of said cup or shell, from which the said lugs extend laterally in opposite directions. 90 These lugs fit into vertical channels k in the side walls of the recess h receiving the said block, the said channels extending from top to bottom of said recess and permitting the said lugs to be lifted up and out 95 through them for freeing at will the said cup or shell and bearing-block, but preventing their accidental lateral displacement. On the bottom of the said cup, shell, or casing L is formed a transverse rounded pivotal rib L' 100 on the line connecting the centers of these lateral lugs. This rib rests on the bottom of 105 said recess, permitting the block to rock

slightly, and thus adjust the line of the V-groove to that of the knife-edge and insuring equal pressure and wear at all points. The metal shell L of course reinforces and 5 protects the agate block instead of weakening it.

M designates an external casing for each pivot, fastened to the standard H by a screw m and having in its front an opening or window m', Fig. 5, behind which a plate of glass 10 is interposed between said front of the casing and the bearing-block I. Since the pivot rests in the groove of the said block, as shown in Fig. 1, the end of said pivot is necessarily in contact with said glass plate. The two glass plates minimize friction at the ends 15 of the pivots, while preventing any lateral movement of the tare-beam and attachments, and thus preventing the contact of said beam with either standard H. The pivot is not 20 shown in Fig. 5, as it would hide a part of the bearing-block and shell and does not seem needed in said view.

The computing-panel G has the same graduation on both faces, these faces being counterparts in all respects, so that the customer may observe the figures indicated at the same time with the seller, though having the panel between them.

30 N designates a pair of counterpart segment-shaped plates which together constitute a sliding attaching-bracket for a pair of pivoted indexes O O', one of said plates and one of said indexes being located on each side of the panel.

35 Each plate N is provided with lugs n, overlapping longitudinal guideways P on the sides of the said panel G, constituting a frame or border for the longitudinal slot G' of said channel, and screws Q R are passed 40 through said plates and slot, holding the two plates in position against the said panel, though not so tightly as to interfere with slipping them along the slot and guideways from point to point. The screw Q is of 45 greater length and size than screw R, adapting it to be passed through the two indexes and to serve as a bearing therefor. Each index has a light plate O² attached to and moving with it, the curved outer edge of each 50 plate O² fitting against a shoulder P², raised on its bracket-plate P or P', the curvature of said edge and shoulder being circular and concentric with a curved series of graduations carried by said bracket-plate, these being 55 preferably on a detachable card. The index O, normally toward the scale-platform, is more finished than the other one and bent near the tip to engage a segmental series of notches N², also concentric with the said 60 graduations. Index O is provided at its rear end with a weighted handle S, serving, with the said plates and indexes, as an additional sliding poise which may be moved to indicate the weight of the material after the poise D 65 aforesaid has been shifted to indicate that of

the pan or containing vessel. Such indication is made by a pair of pointers T, presented upward and downward from a projecting part of the other end of the bracket-plate beyond screw R. These pointers travel over 70 a pair of straight series of graduations arranged, respectively, above and below the slot and guideways aforesaid. The upper series is graduated for pounds, as shown, with blank spaces between, except that the 75 space for the first pound is divided for quarters thereof, with suitable fractional numerals. The lower series has each pound-space divided for ounces avoirdupois. Of course 80 any other measures of gravity may be substituted.

Index O is made in two sections, joined near the middle by a screw S', the rearward section, which has weight S appended thereto, being the heavier and provided with a 85 raised integral hub S², surrounding the screw Q. The light forward section of this index has a raised fin or thumb-piece to facilitate the turning of the indexes by hand. The other index O' carries no weight, has no enlarged section, raised hub, or thumb-piece, and engages no notches, but occupies the same position, moves with the other index, and of course points to the same numbers at 90 the same time.

95 The series of graduations for each plate are preferably double, consisting of red and black numbers arranged alternately, as shown, in two rows of parallel curvature. In shifting the index O from notch to notch it 100 passes also from figure to figure of said scale, this double arrangement making possible the use of more numbers than would otherwise be possible in so small a space with type of proper size. The panel is provided with 105 other double concentric series of numbers, also in two colors and alternate arrangement, each set being concentric with that on the movable bracket-plate and the intervening spaces occupied by concentric series of subdivision-indicating marks, also alternating, the red being above each line, the latter below, or vice versa. These curved series of numbers and graduations on the panel indicate price 110 and are primarily intended for dollars and cents, but may be used for any other monetary denominations—for example, francs and centimes. The indexes are prolonged over and beyond the front of the bracket-plates to indicate numbers on these price series at the same time that they indicate numbers on the similar series of the bracket-plates which stand for the price per pound. The cards of these latter series are set into 115 curved depressions of the faces of said bracket-plates below the curved shoulders aforesaid, and raised curved flanges or walls N³ on the forward edges of the brackets, in one of which walls the notches N², already mentioned, are formed. Also each shoulder 120 130

has a curved lip N^4 , bent in a plane at right angles to it and extended forward over the number-card to hold it in place. Of course these and other structural details may be greatly varied without affecting the main features of our invention.

In operation the goods are first weighed, as above stated. If then the pointer T indicates "2" on the straight series of graduations as the number of pounds and the price is eight cents a pound, the index is turned over "8" on the card of the plate, the series of which indicates the price per pound, the index at the same time engaging one of the notches N^2 for preventing any accidental change of place. The point of said index will then be just over the number "16" in red on one of the curved total-price series of the panel and just above the straight horizontal dividing-line. The rule is that the red numbers and graduations shall be counted when the index-points just above the said dividing-line and over the red graduations of the main chart and the number under the index of the price-per-pound series of the bracket-plate be red. This being true of the "8" in the latter series, we get the result sixteen. Conversely, a black number of the price-per-pound series on the bracket when under the index calls for the point of the index to register slightly below the aforesaid horizontal dividing-line and over the black subdivision graduations and indicating that the black figures of the total-price series of the main chart are to be counted. If then we suppose the price per pound to be seven cents instead of eight and shift the index accordingly, we get the correct result, fourteen. The same rule applies to reading the graduations between the series, red being above the line, black below. If the weight be between two numbers for pounds, the point of the index after turning it over the price per pound will be on the proper line between two curved series of the computing-panel, and the reading will be as before, except that no numerals are affixed to these graduations, and they must be counted or estimated by length, each short one representing one cent and every fifth one standing at twice the length of the others, so it is readily distinguished and represents five cents. These dash graduations in red and black between the different pound-figures from "1" to "10" above and below the horizontal lines of the main chart are subdivided into a number of parts equivalent to the price in cents per pound and are the same in all the pound-spaces along the same horizontal line. To illustrate, suppose we use the black figures below one of the horizontal lines and the price is ten cents per pound. Each pound-division in that line from "1" to "10" is subdivided by nine dashes, each dash representing one cent. If we use the red figures above the line and the price is twelve

cents per pound, the same pound subdivisions above the line are then divided by eleven dashes, each representing one cent, the final pound-mark of course representing the last dash or the tenth and twelfth cent, 70 respectively.

The space before the first double-curved series on the panel corresponding in position to the one-pound mark of straight graduation is subdivided into four vertical curved 75 spaces in which the total price of an ounce, one-fourth, one-half, or three-fourths of a pound are plainly given. These total-price figures are all in black numerals and give the nearest approximate price for both the black 80 and red figures on the pound-divisions of the whole chart for the above-enumerated fractions of pounds. However, when there is too much difference between the black and red numerals of total-pound figures these indicating-numerals are followed by a red dot, always representing one cent, thus indicating, if the red pound price is in use, that one additional cent is put onto the amount of the black numeral. For instance, in the first 85 line of figures above the central dividing-line of the chart and at the left-hand end thereof when the pound is marked in black "21 $\frac{1}{4}$ " directly above the one-fourth-pound indication is the figure "5" in black. Now in these 90 chart calculations when the fraction of a cent is under one-half the customer is given the benefit of the fraction, and when it is one-half cent or over the store takes the benefit of the fraction. In the case above cited where the 95 total pound is twenty-one cents the quarter-pound would be five and one-fourth cents. The store now loses and the black numeral "5" counts. On the other hand, the red figure of this same pound-division 100 is "22," so that the quarter thereof would make five and one-half cents. In this case the store takes the benefit of the fraction and the black one-fourth-pound numeral is followed by a red dot, indicating that an 105 extra cent is to be added to the black numeral "5" when the red pound-numerals are in use.

Having thus described our invention, what we claim as new, and desire to secure by Letters Patent, is --

1. In combination with the frame and tare-beam of a computing-scale, a graduated computing-panel mounted on said beam, a graduated plate attached to, and adapted to slide 120 along, said panel, an index arranged to move pivotally over the latter plate and means for holding the said index at any point of pivotal adjustment, the said index and plate serving also as an additional poise, substantially as 125 set forth.

2. In combination with the frame and tare-beam of a computing-scale, a computing-panel mounted on said beam and having the same graduations and indications on both 130

sides, a pair of graduated plates connected together and moving along the said panel on each side thereof, a pair of indexes arranged to move pivotally over said plates respectively and to be shifted therewith along the panel and means for holding said indexes at any point of pivotal adjustment to which they may be moved.

3. In a computing-scale, a computing-panel provided with curved series of graduations and indications for the total price and with a straight series of indications for weight, in combination with a plate provided with a pointer for said series and having a series of indications for price per unit of weight, and an index shifting along said panel with said plate and turning independently on its pivot over the latter, the said plate and index being weighted to serve as a poise and the said parts and series being relatively arranged so that the shifting of the index to the price-per-pound series will also indicate the total price on the panel substantially as set forth.

4. In a computing-scale, a weighing computing-panel, having on each side a series of graduations for weight and additional series of graduations for total price and further provided at one end with several series of numbers showing the total price of fractional parts of a pound or other chosen unit of weight, these numbers being dotted where the computation is only approximate, in combination with a poise movably mounted on

said panel and provided with numerals in series for the price per pound, also with a pointer for the first series mentioned and an independently-movable index for the other two series substantially as set forth.

5. In a computing-scale, a weighing and computing panel, having on each side a series of characters for indicating weight and another series for indicating total price, in combination with a plate and poise movable along said panel and provided with a series of characters for showing the price per pound or other unit of measure, also with a pointer for the first series mentioned and an independently-movable index for the other two series, each of the latter series consisting of two rows of characters alternately arranged and distinguished from each other, as by color, the two rows taken together constituting in each instance a continuous numerical series and being arranged so that when the plate and poise are in position to ascertain the weight, the shifting of the index over the price per pound will show on the panel the total price substantially as set forth.

In testimony whereof we have signed our names to this specification in the presence of two subscribing witnesses.
